MULTIPLE PRECISION INSTRUMENT
AND TOOL

Victor S. Debs, New York, N. Y.

Application December 16, 1949, Serial No. 133,390

2 Claims. (Cl. 33—102)

1

This invention relates to a multiple precision instrument and tool.

An object of this invention is to provide a highly improved device of the character described which may be used as a six inch rule, having a pair of superimposed portions one of which is provided with ruler scales at opposite edges, one divided into inches and sixteenths of an inch, and the other into inches and tenths of an inch, and the other part of which has ruler scales marked at the opposite edges thereof, one divided into inches and thirty-seconds of an inch and the other side being a metric scale.

Another object of this invention is to provide a device of the character described in which the two parts are extensibly interconnected and said parts being extensible to provide a twelve inch ruler with scales divided into inches and sixteenths of an inch at one edge, and scales at the opposite edge divided into inches and tenths of an inch.

Yet another object of this invention is to provide a device of the character described in which the two parts are interconnected by a sliding pivot and having means thereon to permit the device to be used as a proportional line divider and also as a circle divider.

Yet another object of this invention is to provide a device of the character described in which the parts may be attached together at right angles to one another to provide an adjustable square or the parts attached together at various angles to provide for means for drawing triangles or various angles.

Yet another object of this invention is to provide an angular device of the character described having protractor scale means to measure various angles whereby the device may be used as a protractor.

Yet a further object of this invention is to provide a device of the character described having means to permit the device to be used as a compass for drawing circles from one-half inch to twelve inches in radius.

Still another object of this invention is to provide a device of the character described which may be used either as a letter opener or as a paper cutter.

Yet a further object of this invention is to provide a strong, compact and durable device of the character described which shall have a great many uses, which shall be easy to adjust and manipulate and be efficient to a high degree in use.

Yet another object of this invention is to provide a combination tool which is adaptable for several uses in measuring and drafting work and which shall be simple in construction, accurate in use, easy to operate, and which shall be extremely light in weight, small in size, convenient to carry and which may be manufactured at ex-

2

tremely low cost and which will nevertheless be efficient and practical to a high degree.

Other objects of this invention will in part be obvious and in part hereinafter pointed out.

The invention accordingly consists in the features of construction, combinations of elements, and arrangements of parts, which will be exemplified in the construction hereinafter described, and of which the scope of invention will be indicated in the following claims.

In the accompanying drawings in which is shown various illustrative embodiments of this invention,

Fig. 1 is a top plan view of the device embodying the invention, showing the device in position for use as a six inch rule;

Fig. 2 is a bottom plan view of the structure shown in Fig. 1;

Fig. 3 is a cross-sectional view taken on line 3—3 of Fig. 5 and illustrating the bottom surface of the top section of the device;

Fig. 4 is a cross-sectional view taken on line 4—4 of Fig. 5 and illustrating the upper surface of the bottom section of the device;

Fig. 5 is a side edge view of the device shown in Fig. 1;

Fig. 6 is a top plan view of the device shown in Fig. 1 but with the top and bottom sections extended or opened up;

Fig. 7 is a top plan view of the device shown in Fig. 1 with the top section at right angles to the bottom section shown in full lines and with the top section at an acute angle to the bottom section shown in dot-dash lines;

Fig. 8 is a cross-sectional view taken on line 8—8 of Fig. 1;

Fig. 9 is a partial cross-sectional view similar to Fig. 8 and illustrating a modified construction;

Fig. 10 is a top plan view of the device embodying the invention and illustrating another modified construction;

Fig. 11 is a cross-sectional view taken on line 11—11 of Fig. 10;

Fig. 12 is an enlarged partial view showing the junction of the top and bottom sections when said sections are attached together at right angles to one another to form a T;

Fig. 13 is an enlarged partial top view showing the use of the device as a protractor;

Fig. 14 is a top plan view showing the device in use as a proportional divider;

Fig. 15 is a top plan view showing the use of the device as a circle divider;

Fig. 16 is a perspective view illustrating the use of the device as a compass for circles of less than $3\frac{1}{2}$ " radius;

Fig. 17 is a perspective view of the device showing the use of the device as a compass for circles having radius from $3\frac{1}{2}$ " to 6";

Fig. 18 is a view similar to Fig. 17 but illus-

trating the use of the device as a compass for circles of a radius from six to twelve inches;

Fig. 19 is a perspective view illustrating the use of the device as a letter opener; and

Fig. 20 is a perspective view illustrating the use of the device as a paper cutter.

Referring now in detail to the drawing, 10 designates a device embodying the invention. The same comprises a top part or section 11 and a bottom part or section 12. The top section 11 has a top surface 13 having a triangular shaped end pointed portions 13a and 13b. Extending downwardly and rearwardly from the top surface 13 is a beveled surface 14 terminating in an edge 15. Extending downwardly and forwardly from the top surface 13 is a beveled surface 16 terminating in an end edge 17. Extending from surface 13a are beveled surfaces 18 and 19 terminating in edges 20 and 21 respectively. The edges 20 and 21 meet at a point 22. The surfaces 18 and 19 meet at an edge 23. Extending from the surface 13b are beveled edges 24 and 25 terminating in inclined edges 26 and 27. The edges 26 and 27 meet at a point 28. The surfaces 24 and 25 meet at an edge 29.

Said top member 11 is furthermore formed adjacent one end with longitudinal central slot 31 forming opposite parallel edges 32 and 33. Extending from the edges 32 and 33 are upwardly and outwardly inclined surfaces 32a and 33a respectively. The slot 31 extends into the surface 13b at one end and is of a length of somewhat more than half the length of the member 11 as will be explained hereinafter.

On the surface 14 is marked a scale 36 which may be divided into inches and sixteenths of an inch. On the surface 16 is a scale 37 which is divided into inches and tenths of an inch. The length of the scales 36 and 37 is six inches exactly.

The angle between the edges 20 and 21 is preferably sixty degrees. Likewise the angle between the edges 26 and 27 is preferably sixty degrees. Member 11 is formed with vertical through opening 39 at the junction of surface 13a with the edge 23. Said member 11 is also formed with a vertical through opening 40 at the junction of surface 13b and edge 29. The openings 39 and 40 may be tapered if desired. It will now be noted that the slot 31 extends from a point beyond one end of scales 36, 37 to a point beyond the $3\frac{1}{2}$ " marks on said scales.

On surface 13 and adjacent the surface 32a is marked a line proportional divider scale 41, in proportions of $\frac{3}{4}$ to 1; $\frac{2}{3}$ to 1, 2 to 1, 3 to 1, 4 to 1, 5 to 1, 6 to 1, 7 to 1, and 8 to 1. Adjacent one end of the scale may be marked the word "Lines."

On surface 13 and adjacent the surface 33a is a circle divider scale 42 having indications for dividing a circle into 6, 7, 8, 9, 10, 11, 13 and 15 parts. The use of the device as a proportional divider for lines and as a circle divider will be explained in detail hereinafter.

The part 11 has a bottom surface 43 shown in Fig. 3 of the drawing. Said surface 43 is marked with a horizontal line 44 extending from the axis of hole 39 to the point 22. It is also formed with a horizontal line 45 extending from the center of the circle 40 to the point 28.

Marked on the surface 43 adjacent one end thereof is the major portion of a circular protractor scale 46. The center of the scale 46 is located within slot 31 adjacent one end thereof. It will be noted that the zero and 180 degree angle lines of the scale 46 passes through the junctions of the lines 26, 18 and 21, 17 respec-

tively. It will also be noted that the scale 46 is not a complete circle as part of it is cut off by the slot 31.

Referring now to the section or part 12, the same is superimposed beneath the part 11 and is similar in shape thereto and is symmetrically disposed with respect thereto. The part 12 has a top surface 50 which contacts the surface 43 of part 11 as shown in Fig. 4 of the drawing. Thus part 12 has an edge 51 which coincides with the edge 15, an edge 52 which coincides with the edge 17, edges 53 and 54 each coincide with the edges 20 and 21 respectively, and edges 55 and 56 each coincide partly with the edges 26 and 27 respectively. Between the edges 55 and 51 is a notch 57. Between the edges 56 and 52 is a notch 58. Notch 57 forms an edge 57a at right angles to the edge 51. Notch 58 forms an edge 58a at right angles to the edge 52 and aligned with edge 57a. On surface 50 and adjacent the edge 51 is marked scale 59, six inches in length and divided into inches and tenths of an inch. On said surface 50 and adjacent the edge 52 is marked a scale 60, six inches in length and divided into inches and sixteenths of an inch.

The part 12 is formed with longitudinal slot 61 similar and symmetrically disposed with respect to the slot 31 and coinciding therewith. Slot 61 forms opposite parallel edges 62 and 63. Extending from the edge 62 is a downwardly and outwardly beveled surface 62a. Extending from edge 63 is a downwardly and outwardly beveled surface 63a.

The underside of part 12 is illustrated in Fig. 2 of the drawing. Said part has a bottom surface 66 similar to the surface 13 and part 11. Extending from surface 66 are opposite beveled edges 67 and 68 symmetrical to the surface 16 and 14. On surface 67 is a scale 69, six inches in length and divided into inches and sixteenths or thirty-seconds of an inch. On surface 68 is a scale 70 which may be a metric scale. Surface 66 has a triangular portion 66a at one end, and a triangular portion 66b at its opposite end. Extending from the surface 66a are beveled inclined surfaces 72 and 73 extending to the edges 54 and 53 respectively. Extending from the surface 66b are surfaces 74 and 75 extending to the edges 56 and 55 respectively. Edges 53 and 54 meet at a point 71. Edges 56 and 55 meet at a point 78. The surfaces 72 and 73 meet at an edge 79. The surfaces 74 and 75 meet at an edge 80. On surface 66 and adjacent the surface 63a is a scale 81 which starts one-half inch away from the right end of edge 68 and extends to the $3\frac{1}{2}$ " mark, and is divided into inches and sixteenths of an inch.

On surface 66 and adjacent the surface 62a is a scale 82 coextensive with the scale 81 and likewise divided into inches and sixteenths of an inch. It will be observed however that while scale 81 is from $\frac{1}{2}$ " to $3\frac{1}{2}$ " reading from right to left, the scale 82 is from $3\frac{1}{2}$ " to $6\frac{1}{2}$ " reading from left to right. The $3\frac{1}{2}$ " mark on scale 82 is opposite the $3\frac{1}{2}$ " mark on scale 81. Thus the 4", 5" and 6" marks on scale 82 are opposite the 3", 2" and 1" marks respectively on the scale 81.

The part 12 is formed, furthermore, with an opening 83 at the junction of surfaces 66a and the edge 79. The opening 83 may be tapered and registers with the opening 39 when the parts 11 and 12 are superimposed. Said part 12 is furthermore formed with an opening 84 at the junction of surface 66b and edge 80. Said open-

ing may be tapered and registers with the opening 40 when the parts 11 and 12 are superimposed.

Means is provided for slidably and pivotally connecting the parts 11 and 12 and for attaching said parts in various adjusted positions. To this end there is provided a slider "S". The slider "S" comprises a part 85 mounted in the slot 61, having a beveled surface contacting the surfaces 62a and 63a and a bottom surface flush with the surface 66. Marked on the undersurface of the slider part 85 is a line 86 which registers with the $\frac{1}{2}$ " mark on the scale 81 and the $6\frac{1}{2}$ " mark on the scale 82 when said member 85 is at the right end of part 12, looking at Fig. 2 of the drawing. Said undersurface of member 85 is also provided with a horizontal line 85a at right angles to the line 86 and extending to an end edge of said part 85.

Fixed to or passing through an axial hole in part 85, is a screw 87 passing through slot 31 and upwardly above surface 13. Screw 87 is held against rotation relative to slider part 85. At the upper end of the screw 87 is a point 88. Within slot 31 is a slider part 89 substantially similar and symmetrically disposed with respect to part 85. On the upper surface of part 89 is a line 89a which can be used with either scales 41 or 42. Part 89 has beveled surfaces contacting the beveled surfaces 32a and 33a. It is formed with a through opening through which the screw 87 passes. It has a top surface flush with the surface 13. Screwed to the screw 87 is a nut 90. When the nut 90 is tightened the parts 85 and 89 are pressed together for pressing the parts 11 and 12 together. Upon loosening the nut 90 the slider "S" may be slidably moved relative to slots 31, 61.

Furthermore the parts 11 and 12 may be pivotally moved relative to one another about the axis of screw 87. Furthermore the two devices may be extended. Thus the parts 11 and 12 may be moved from superimposed positions as shown in Figs. 1 and 2, to extended positions shown in Fig. 6, or to a right angular or other angular position and shown in Fig. 7. A right angle position of the two parts forming a T is shown in Fig. 12. In Fig. 13 the two parts are at right angles to one another, meeting at a corner so the device can be used as a protractor. In Figs. 14 and 15 the two parts cross each other for use as a line proportional divider.

The various uses of the device will now be described in detail.

When the parts 11 and 12 are attached together in superimposed position, the device can be used as a six inch ruler. Either the scales 36, 37, 69 or 70 can be used. The device can also be used for slitting folded paper because of the beveled longitudinal edges. Upon loosening the nut 90 and swinging the bottom section through 180 degrees about the screw and then again tightening the nut, the device may be used as a 12" ruler with $\frac{1}{16}$ and $\frac{1}{16}$ inch graduations. In said position the scales 69 and 59 will be in tandem and the scales 60 and 36 will be in tandem.

To use the device as a proportional divider for lines, superimpose parts 11 and 12, loosen the nut and push the slider "S" until the line 85a registers with the desired ratio on the scale 61. Then tighten the screw and the device can be used as a proportional divider, as illustrated in Fig. 14. The lines on the point ends of the ruler are the guides to be considered in measuring. The ends on the slotted sides represent

the reduced ratio. The points 11, 22 and 78, 28 are the points which are to be used.

For using the device as a circle divider, merely move the slider to bring line 89a to the desired point on the scale 42. The use of the device as a circle divider is illustrated in Fig. 15 of the drawing.

To adjust the device for use as a square, loosen the screw and turn one arm of the ruler 90 degrees to obtain a square. One square is illustrated in Figs. 7 and 12. In such position the line 85a on the undersurface of part 85 will register with the 180 degree mark on the protractor scale 47, as illustrated in Fig. 12. In the position of Figs. 7 and 12 the part 12 is at right angles to part 11 and the slide "S" has been moved to the inner end of the slots 31, 61.

Obviously, part 11 may be moved to any desired angle with respect to part 12 and the angle is indicated on the protractor scale 46 and can be read at line 85a. As shown in Fig. 12, the part 11 is at the middle of part 12. If desired the slider "S" may be moved lengthwise of the part 12 and the nut tightened in any desired position.

In Fig. 13 the device is illustrated when used as a protractor to measure angles of any degree. As shown in Fig. 13, the slider "S" is at one end of the slot 61 in part 12. The part 11 may be rotated about the screw, and the angle on the protractor scale 46 may be read at the edges 57a or 58a. It will be noted that the undersurface of part 89 of the slider "S" is marked as at 89b with a scale which complements the portion of the scale 46 that is omitted by reason of the slot 31. In other words, when the part 89 is at the right end of the slot 31 as shown in Fig. 3, the scale 89b completes the scale 46 and the two scales together make a circle of 360 degrees. In Fig. 13 the protractor reads 90 degrees at the edge 58a. However by rotating member 11 relative to member 12 any other desired angle may be obtained and the angle will be read either on scale 46 or scale 89a, wherever the edge 58a happens to be located.

In Fig. 16 the device is illustrated as being used as a compass for circles having radius from $\frac{1}{2}$ " to $3\frac{1}{2}$ ". To accomplish this function, the parts 11 and 12 are superimposed. The slider is moved to bring the mark 86 into registry with the desired radius on scale 81 from $\frac{1}{2}$ " to $3\frac{1}{2}$ ". The device is then held upside down so that the point 88 can penetrate the center of the circle to be drawn. The point of a pencil "P" is then inserted through the holes 40, 80 and using the point 88 as a center of rotation, the device 10 is rotated to draw the circle "C".

If it is desired to draw a circle with a radius from $3\frac{1}{2}$ " to $6\frac{1}{2}$ " the point of the pencil "P" is inserted through the registering openings 39, 83. The slider is moved to bring the line 86 into registry with the desired reading on scale 82 which is from $3\frac{1}{2}$ " to $6\frac{1}{2}$ " and the circle "C" is made. For circles of $6\frac{1}{2}$ " to 12" radius, open the ruler by swinging part 12 180 degrees relative to part 11 so that the parts 11 and 12 are in alignment. The two parts are slidably moved relative to one another to obtain desired circle radius. The pin "N" is then inserted through the hole at one end of part 12 and the point of the pencil "P" inserted through the opening at the other end of part 11. Circle "C" may then be drawn.

In Fig. 19 it is shown how either part 11 or part 12 can be used as a letter opener because of its beveled edges. Furthermore the device may be

used as a paper cutter to cut paper in scissors-like fashion.

In Fig. 9 there is shown a device 10a illustrating a modified construction. The device 10a is similar to device 10 with the exception that instead of having beveled surfaces between the slider and the ruler parts, a right angle step construction is used as indicated at 100 and 101.

In Figs. 10 and 11 there is illustrated a device 10b showing a still further modified construction. The device 10b can be used as a slide rule. It comprises a top part 102 and a bottom part 103 similar to parts 10 and 11, except that the slots in said parts cross the entire length of said parts. The slot in the top part 102 is wider than the slot in the bottom part. Said slot in the top part 102 has beveled surfaces 104 and the slot in the bottom part 103 may have a step construction as shown at 105.

The slider "S" used with the part 10b comprises a slider part 106 sliding in the slot in the lower member 103 and affixed thereto is a screw 107 passing through the slider part 108 in the slot of part 102. Screwed on the screw in a nut 90. It will now be observed that portions of the upper surface of the part 103, on opposite sides of the slot therein, are exposed and may be seen through the slot in the top part 102. These exposed surfaces may carry slide rule scales, and the inclined surfaces 104 on the part 102 may carry slide rule scales cooperating therewith. These scales may be "A," "B," "C" and "D" scales of a slide rule.

It will now be observed that the device 10b comprises two parts which are slid able one longitudinally of the other, and a slider, and when marked with the proper scales the device may be used as a slide rule. The parts 102 and 103 have outer beveled edges and pointed ends and are constructed like the parts 11 and 12 except as noted hereinabove.

It will thus be seen that there is provided a device in which the several objects of this invention are achieved and which is well adapted to meet the conditions of practical use.

As various possible embodiments might be made of the above invention, and as various changes might be made in the embodiment above set forth, it is to be understood that all matter above set forth, or shown in the accompanying drawings is to be interpreted as illustrative and not in a limiting sense.

Edges 23, 29, 79 and 80 are marked with lines.

On the upper surface of part 12 (Fig. 4) are marked horizontal lines 44a and 45a extending to points 77 and 78 respectively. It will now be understood that the lines 44, 45, 44a, 45a, 23, 29, 79 and 80 all extend to the points of the parts 11 and 12 to serve as markings to facilitate use of the device as dividers.

The holes 39, 40, 83 and 84 are tapered to facilitate inking. The beveled edges of the parts 11 and 12 also facilitate inking.

Having thus described my invention I claim as new and desire to secure by Letters Patent:

1. A device of the character described comprising a pair of superimposed rules formed with registering longitudinal slots, means extending through said slots for interconnecting said rules for independent sliding as well as independent pivotal relative movement, said means being further provided with means for clamping said rules together in various adjusted positions, said rules each being formed at the exposed sides thereof with beveled opposite surfaces extending to op-

posite edges thereof, said rules each having pointed ends, scales on the beveled surfaces of said rules, and scales at opposite edges of the inner surface of one of said rules, one of said rules being provided with a line proportional divider scale adjacent one edge of the longitudinal slot therein, said last mentioned rule being formed with a circle divider scale adjacent the opposite edge of the longitudinal slot therein, and means on the slider to cooperate with said proportional divider scale and circle divider scale, the other rule being provided with scales to measure lengths at opposite edges of the longitudinal slot therein, and means on the slider to cooperate with said last mentioned scales, the first rule being formed adjacent one end thereof and at the inner surface thereof with a protractor scale, formed partly thereon and partly on the slider which rides freely in said longitudinal slot.

2. A device of the character described comprising a pair of superimposed rules formed with registering longitudinal slots, means extending through said slots for interconnecting said rules for independent sliding as well as independent pivotal relative movement, said means being further provided with means for clamping said rules together in various adjusted positions, said rules each being formed at the exposed sides thereof with beveled opposite surfaces extending to opposite edges thereof, said rules each having pointed ends, scales on the beveled surfaces of said rules, and scales at opposite edges of the inner surface of one of said rules, one of said rules being provided with a line proportional divider scale adjacent one edge of the longitudinal slot therein, said last mentioned rule being formed with a circle divider scale adjacent the opposite edge of the longitudinal slot therein, and means on the slider to cooperate with said proportional divider scale and circle divider scale, the other rule being provided with scales to measure lengths at opposite edges of the longitudinal slot therein, and means on the slider to cooperate with said last mentioned scales, the first rule being formed adjacent one end thereof and at the inner surface thereof with a protractor scale, the other rule being formed with a notch forming an edge adapted to cooperate with said protractor scale, said slider being provided with part of a protractor scale complementary to the protractor scale on the first scale.

VICTOR S. DEBS.
